UNITED STATES PATENT OFFICE.

NIC KRUMP, OF OAK, ALABAMA.

PROCESS OF ERECTING CONCRETE BUILDINGS.

Application filed August 19, 1925. Serial No. 51,235.

In erecting concrete buildings moulds are used, between the vertical walls of which a wet mixture of sand and concrete, herein-after termed a concrete mixture, is poured, 5 to obtain the walls of the building, the window and door frames of the building being properly placed between said vertical walls to be embedded in the concrete obtained by the "setting" of said mixture, and in erect- 10 ing a building by this process said moulds and additional ones are employed whereby the walls erected by this process contain vertical spaces which are sealed at their upper and lower ends, and a substantially 15 horizontal mould, having sides and ends, is used to obtain the roof of the building, together with additional moulds whereby a number of sealed spaces are obtained in said roof.

20 Among the objects of this invention is to obtain a process whereby the walls of the building have sealed air spaces extending vertically from substantially the base of the walls to the top thereof, or substantially so; 25 said walls provided with door and window frames embedded therein, and the walls below said window frames being provided with similar sealed air spaces extending from substantially the base of the wall to 30 the lower horizontal members of said window frames, and from the top horizontal member of said door and window frames to substantially the top of said walls. A fur- 35 ther object is to obtain a process whereby the walls of the building will contain rein- forcing rods and wires, and the inner and outer portions of the walls will be substan- 40 tially separated by the air spaces in said walls, and joined together by metal ties. An additional object is to obtain a process of 45 erecting buildings whereby the roof of the building will contain a number of air spaces, with concrete above, below and between said air spaces. An additional object is to ob- 50 tain a building erected by my process the outer portion of the walls whereof will not crack or become injured by rain, snow, or considerable variation in climatic tempera- 55 ture in the day and in the night; and a concrete building whereof the inner portion 60 of the walls will be dry, and not affected by the wetting or moisture of the outer por- 65 tion of the wall, as by rain or snow.

I have illustrated my invention applied to the erection of a concrete building in the 55 drawings referred to, in which:—

Fig. 1 is a perspective of a portion of the side walls and roof of a partially erected building being constructed by my process; parts being broken away and removed to 60 show the several members used in the construction of the building and the parts forming the elements of the building, and their relation to each other.

Fig. 2 is a plan view of a metal sheet 65 which is formed up to form a mould for obtaining the air spaces in the walls of the building.

Fig. 3 is a perspective, on an enlarged scale, of the mould obtained from the sheet 70 of metal illustrated in Fig. 2, and of a removable brace applied to said mould when the same is in position to be embedded in the walls formed by the pouring of a cement mixture around it.

Fig. 4 is a top plan view of a section of a wall, taken on line 4—4 of Fig. 5, viewed as indicated by arrows.

Fig. 5 is a vertical section of the section 80 of wall illustrated in Fig. 4, taken on line 5—5 of Fig. 4, and viewed in the direction indicated by arrows.

Fig. 6 is a top plan view of a section of the roof of the building being erected, with portions of the several elements forming the 85 roof removed, to show the construction thereof and the relation of said elements to each other, and

Fig. 7 is a vertical sectional view of the section of the roof which is illustrated in 90 Fig. 6, taken on line 7—7 of Fig. 6, and viewed in the direction indicated by arrows.

A reference character applied to designate a given part indicates said part where- 95 ever the same appears throughout the sev- eral figures of the drawings.

1, Fig. 2, represents a sheet of metal, which is formed up substantially on broken lines 2, to obtain the collapsible mould 3, illustrated in perspective in Fig. 3, and shown in Figs. 1, 4 and 5. The ends 4 of the collapsible mould 3 are rounded. 5 represents a piece of grooved and tongued flooring, which is of substantially the same length as the height of mould 3. 6 repre- 100 sents one end of the blank 1, which is bent 105

inward to form a member adapted to fit in the groove of member 5. When member 5 is in the position illustrated in Fig. 3 and as shown by full lines in Figs. 4 and 5, said mould 3 is not collapsible; but when said member 5 is forced into the position indicated by the broken lines 7, in Fig. 4, it may be collapsed sufficiently to loosen the rounded ends 4, so that said mould can be removed from the partially set concrete mixture surrounding it.

To construct walls by this process a trench is dug, and the base 8, Fig. 5, is poured from a concrete mixture, and allowed to partially set. The outer moulds 9, 10, are built up on said base, to a height substantially corresponding with the height of mould 3, and said moulds are set on said base, together with reinforcing material 11, 20 and reinforcing tie members 12. The vertical reinforcing rods 13 are also set in place, the lower ends thereof preferably forced into the base 8. Said reinforcing rods 13 being positioned while said base is sufficiently plastic to permit said rods to be forced thereinto. A concrete mixture is then poured between moulds 9 and 10, and around moulds 3, and around and over the several reinforcing material and rods, to near the upper edges of moulds 3. The mixture is allowed to partially set, so as to retain its form, and thereupon members 5 are removed from moulds 3, and said moulds are raised, so that the lower edges thereof extend a short distance below the upper surface of said concrete. The moulds 9 and 10 are raised, or built up, (as preferred), so that the upper edges thereof are at substantially the same level as the upper edges of moulds 3. Additional reinforcing members are then placed in position between moulds 3 and 9 and 10, and additional concrete mixture is poured, as before.

The foregoing process is continued until the walls are completed.

14, Fig. 4, represents a member of a door casing, and 15, 16 mould boards which extend from moulds 9 and 10, respectively, to said casing 14. When the concrete mixture is poured as hereinbefore recited, the casing 14 becomes embedded in the wall.

When the walls have been erected to a determined height in the manner hereinbefore described, the moulds 3 are removed, and the upper ends of the several air spaces formed thereby are covered, as by a thin sheet of metal. The substantially horizontal mould bed, 17, Fig. 7, is then erected, with the upper face thereof a short distance below the upper ends of the walls, both on the inside of the walls, and on the outside of the walls. Said mould bed on the inside of the walls extends from wall to wall, and on the outside of the walls a distance corre-

sponding with the cornice desired. The portion of the mould bed outside of the walls is provided with sides corresponding with the total thickness of the about to be constructed roof. The concrete mixture is then poured on the mould bed, and reinforcing rods (18, Figs. 6 and 7), are, laid in position, and additional concrete mixture poured thereover to obtain the determined thickness on the lower side of the roof. Reinforcing rods 19 are then placed in position and partially embedded in the concrete; and moulds 20 are then placed on the concrete mixture, to obtain substantially similar spaces between said moulds. Additional concrete mixture is then poured in said spaces between moulds 20 to a determined height. The last named mixture is allowed to partially set, at least sufficient to permit the withdrawal of the moulds 20 without disturbing the concrete walls around the several spaces which are obtained by the removal of said moulds. The upper ends of said spaces, (designated by Figure 21 in Figs. 6 and 7), are then covered by a layer of building paper, 22, which extends entirely over the roof. A layer of woven wire, 23, is then placed on the building paper 22. A concrete mixture (23^a), is then poured on to the woven wire and building paper, to obtain a determined depth, and the additional reinforcing members 24, 25, are placed on said mixture. Additional concrete mixture, 24^a, is then poured over said additional reinforcing members and on to said thin layer of concrete, to obtain the desired depth of concrete, and all the concrete mixture in the roof is allowed to firmly set. The mould bed 17 is then removed and the walls and roof of the building are completed.

By using proper material, with or without designs thereon, as preferred, on the upper face of mould bed 17, the under surface of the roof serves as a ceiling to the rooms and walls of the building.

26 represents an I-beam, which I use when the distance from wall to wall is so great that the roof constructed as described is liable to sag or give way.

I claim:—

The process of constructing a roof to a building which comprises the pouring of a concrete mixture on a mould bed and between moulds in spaced relation to each other and to said mould bed, withdrawing said moulds from said concrete, placing building paper over said concrete and over the spaces formed by the moulds, placing wire netting and reinforcing material over said paper, and pouring additional concrete mixture over said paper, said wire netting and said reinforcing material.

NIC KRUMP.
